CLOSURE MOUNTING MEANS FOR UNDERFLOOR WIRING DUCTS

Thomas W. Murray, 357 Cortleigh Blvd.,
Toronto, Ontario, Canada
Filed May 25, 1962, Ser. No. 197,715
3 Claims. (Cl. 138—92)

This invention relates to closure supporting elements for underfloor wiring ducts.

In underfloor wiring systems, it is common practice to provide accessible closure plates either directly on the wiring ducts themselves or on other openings leading to the ducts whereby access to the ducts may be readily effected. It is necessary, of course, to provide mountings for the plates in association with the ducts. Since pouring of the concrete or like floor must occur subsequently to the installation of the wiring ducts, damage to or marring of the closure mountings frequently takes place.

It is an object of this invention to provide a closure mounting strip for underfloor wiring ducts which is of simple structure and which may be readily employed to present an unmarred exposed surface in the finished floor.

In accordance with the invention, there is provided a closure mounting strip having opposed side faces and opposed longitudinal edges, and a flange adjoining each said edge and extending angularly from and contiguous to the adjoining one of said side faces, each said flange being substantially coextensive in length with said strip, each said flange having a planar edge surface in substantially parallel spaced relation to the adjoining one of said side faces, one of said flange edge surfaces being spaced from the adjoining one of said side faces a greater distance than the other of said flange edge surfaces is spaced from the adjoining one of said side faces, whereby said strip may be selectively positioned to present flanges of varying height.

The invention will be described with reference to the accompanying drawing, in which,

FIGURE 1 is a sectional elevation of an underfloor duct and associated elements in accordance with the invention, and

FIGURE 2 is a plan view.

In the drawing, the underfloor duct shown comprises a bottom channel member 1 having a bottom wall 2, side walls 3, and longitudinal edge flanges 4, and top members 5 each having a side wall 6 in overlapping engagement with a side wall 3, a flange 7 overlying a flange 4 and a vertically disposed lip 8 extending upwardly from flange 7.

In the particular form of duct illustrated, the vertical height thereof is adjustable by moving the top members up or down relatively to the bottom channel 1 by means of adjusting screws 9, the elements being secured in adjusted position by means of hold down screws 9a.

The closure mounting strip in accordance with the invention comprises a metal or like strip 10 having opposed side faces 11 and 12 and opposed longitudinal edges 13. A flange 14 extends perpendicularly from side face 11 adjoining an edge 13, and a flange 15 extends perpendicularly from side face 12 adjoining the other edge 13. The flanges 14 and 15 are of different height, i.e., flange 14 has a longitudinal edge 16 lying in a plane spaced from the adjoining face 11 a greater distance than the spacing between the longitudinal edge 17 of flange 15 from the side face 12. The difference in height is that of the thickness of the finishing floor tile or like covering indicated at 18. For instance, this difference may be one-eighth inch. The flanges 14 and 15 are coextensive in length with the strip 10.

The duct cover plate is indicated at 19.

In use, with the adjusted duct in position in the floor, a strip 10 is placed upon each flange 7 of the top members

2

5 with the face 12 thereof in engaging or facing relation to the flange 7. Each flange 15 is thus upwardly directed and is in substantial engagement with a lip 8 and each flange 14 is downwardly directed and in substantial engagement with the opposed portion of a side wall 6.

The height of each flange 15 is such that its edge 17 is substantially flush with the edge of lip 8. The cover plate 19 may then be placed in position with its side edge portions engaging and overlying the side faces 12. It will be observed that the exposed face of cover plate is substantially flush with the edges 17 of the mounting strips.

The concrete or other cementitious flooring material 20 is then poured whereby the exposed face 21 thereof is substantially flush with the exposed face of the cover plate, the edges 17 of the mounting strips, and the edges of lips 8. No special care need be taken to protect the longitudinal edges 17 during the pouring or travelling steps incidental to the laying of the flooring material 20.

When the floor 20 is completed, the cover plate 19 is removed and the strips 10 are reversed in position. In other words, each strip 10 is turned to place its face 11 in engaging relation with flange 7 and its face 12 exposed, in such position flange 14 is upwardly directed and engaging a lip 8 and flange 15 is downwardly directed. In this position, it will be observed that the edges 16 of the strips are spaced above the exposed face 21 of the concrete floor 20. Since the edges 16 have been disposed within the duct during the placing of the floor 20, they will be in fresh, clean and unmarred condition when the strips 10 are placed in reverse position. The cover plate 19 is then replaced and the floor covering 18 laid with its exposed face 18a substantially flush with the edges 16 of the mounting strips. Each face 11 and 12 may be provided with a sealing gasket 22.

35 It will be observed that the right hand side of FIGURE 1 illustrates the position of strips 10 during the placing of floor 20 while the left hand side of FIGURE 1 illustrates the position of the strips in the finished floor.

I claim:

1. A closure mounting means for underfloor wiring ducts which comprises a strip having opposed side faces, opposed longitudinal edges, and a flange adjoining each said edge, one of said flanges extending angularly from and continuous to one of said side faces and the other of said flanges extending angularly from and contiguous to the other one of said side faces, each said flange being substantially coextensive in length with said strip, each said flange having a planar edge surface in substantially parallel spaced relation to the adjoining one of said side faces, one of said flange edge surfaces being spaced from the adjoining one of said side faces a greater distance than the other of said flange edge surfaces is spaced from the adjoining one of said side faces whereby one of said flanges is of greater height than the other of said flanges, and means forming a generally horizontal supporting surface for said strip, said strip having a first position on said supporting surface wherein one of said side surfaces of said strip is seated thereon and a second position on said supporting surface wherein the other of said side surfaces of said strip is seated thereon whereby in said first position said flange of lesser height projects above said supporting surface and in said second position said flange of greater height projects above said supporting surface.

2. In an underfloor wiring duct having a top opening, a horizontally disposed supporting surface defining at least in part said top opening, a lip extending upwardly from said supporting surface, and a closure plate arranged for support on said supporting surface, closure mounting means comprising a strip having opposed side faces, opposed longitudinal edges, and a flange adjoining each said edge, one of said flanges extending angularly from and

contiguous to one of said side faces and the other of said flanges extending angularly from and contiguous to the other one of said side faces, each said flange being substantially coextensive in length with said strip, each said flange having a planar edge surface in substantially parallel spaced relation to the adjoining one of said side faces, one of said flange edge surfaces being spaced from the adjoining one of said side faces a greater distance than the other of said flange edge surfaces is spaced from the adjoining one of said side faces, whereby one of said flanges is of greater height than the other of said flanges, and means forming a generally horizontal supporting surface for said strip, said strip having a first position on said supporting surface wherein one of said side surfaces of said strip is seated thereon and a second position on said supporting surface wherein the other of said side surfaces of said strip is seated thereon whereby in said first position said flange of lesser height projects above said sup-

10
15

porting surface and in said second position said flange of greater height projects above said supporting surface.

3. A closure mounting means as defined in claim 2, said strip flange of lesser height having an edge substantially flush with the edge of said lip when one of said side faces is seated upon said supporting surface, said strip flange of greater height having an edge projecting above said lip edge when the other of said side faces is seated upon said supporting surface.
